(57) **CLAIM**

The ornamental design for a closed compression-type coaxial cable connector, as shown and described.

DESCRIPTION

FIG. 1 is a perspective view of a closed compression-type coaxial cable connector, in a closed position, showing my new design;

FIG. 2 is a side elevation view thereof, with the opposite side elevation view being a mirror image thereto;

FIG. 3 is a top plan view thereof; and,

FIG. 4 is a bottom plan view thereof.

The broken line showing unclaimed subject matter of the internal elements is for illustrative purposes only and forms no part of the claimed design.
